(57) CLAIM

I claim the ornamental design of a bellman's cart, as shown and described.

DESCRIPTION

FIG. 1 is a perspective view of a bellman's cart showing the new design;

FIG. 2 is a front view of a bellman's cart thereof;

FIG. 3 is a right side view of a bellman's cart thereof;

FIG. 4 is a back view of a bellman's cart thereof;

FIG. 5 is a left side view of a bellman's cart thereof;

FIG. 6 is a top plan view of a bellman's cart thereof; and,

FIG. 7 is a bottom view of a bellman's cart thereof.

The dotted lines are intended to show features that are environmental only and form no part of the claimed design.
